(57) **CLAIM**

The ornamental design for a drinking vessel, as shown and described.

DESCRIPTION

FIG. 1 is a top front perspective view of a drinking vessel showing my new design;

FIG. 2 is a bottom front perspective view thereof;

FIG. 3 is a top rear perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof;

FIG. 9 is bottom view thereof; and,

FIG. 10 is a top front perspective thereof in an alternative position.

1 Claim, 10 Drawing Sheets
